CLAIM

The ornamental design for a tool attachment device as shown and described.

DESCRIPTION

FIG. 1 is a perspective view of a tool attachment device embodying our new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof;

FIG. 7 is a bottom plan view thereof;

FIG. 8 is an enlarged and partial bottom-right side perspective view thereof;

FIG. 9 is an enlarged and partial bottom-left side perspective view thereof;

FIG. 10 is a side cross-sectional view thereof; and,

FIG. 11 is an opposing side cross-sectional view thereof.

The even broken lines in the drawings illustrate portions of the tool attachment device that form no part of the claimed design. The dash-dot broken lines in the drawings illustrate boundaries of the claimed design.

1 Claim, 11 Drawing Sheets
